UNITED STATES PATENT OFFICE.

CHRIST LARSEN, OF BILLINGS, MONTANA.

MINE-LAYING DEVICE.

1,264,818.

Specification of Letters Patent. Patented Apr. 30, 1918.

Application filed December 31, 1917. Serial No. 209,697.

To all whom it may concern:

Be it known that I, CHRIST LARSEN, a citizen of the United States, residing at Billings, in the county of Yellowstone, in the 5 State of Montana, have invented certain new and useful Improvements in Mine-Laying Devices, of which the following is a specification.

This invention relates to improvements in 10 submarine craft and it is the principal object of the invention to provide an attachment for submersible vessels whereby to permit the laying of mines or like explosive devices when the vessel is submerged, 15 thus, rendering such operations less liable to detection by an enemy or other observer and also rendering it possible to attach explosive devices to the hulls of vessels without detection.

20 Another and equally important object of the invention is to provide novel means for retaining marine mines in position upon the sides of the vessel and permit the same to be readily removed by an operator as desired.

It is also an object of the invention to provide means for enabling an operator to leave the vessel while submerged without allowing the passage of water thereinto, in 30 order that the placing or laying of the explosive devices can be accomplished.

Other independent objects are to provide features of construction of portions of the attachment which tend toward the attainment 35 of the above aims irrespective of the relation in which they are used.

Other objects will be in part obvious and in part pointed out hereinafter.

The invention accordingly consists in the 40 features of construction, combinations of elements and arrangement of parts which will be hereinafter set forth, and the scope of application of which will be indicated in the following claims.

45 In the accompanying drawings, wherein is shown one of various possible embodiments of my invention:

Figure 1 is a plan of a submarine vessel having parts shown in section,

50 Fig. 2 is a fragmentary side elevation of the same showing a portion of one of the improved attachments,

Fig. 3 is a vertical transverse section of the same,

Fig. 4 is a vertical longitudinal section 55 therethrough, and

Fig. 5 is a transverse section through the attachment showing the arrangement of a mine therein.

Having more particular reference to the 60 drawings, in connection with which like reference characters will designate corresponding parts throughout the several views thereof, 1 represents a submarine vessel in its entirety, the opposite sides of which 65 have substantially horizontally disposed tubes 2 secured thereto. The forward ends of these tubes 2 are provided with hinged closures 3, which closures, as will be noted, conform in shape to their respective tubes 70 and have the ends of cables secured to the inner sides of the same at points in proximity to the free ends thereof; the remaining ends of said cables extending into engagement with the winding drums of 75 windlasses 4 secured to adjacent portions of the sides of the vessel. In this connection, it is to be noted that the windlasses 4 are arranged in positions such as will permit the same to be housed by the hinged closures 3 80 when the same are swung to their closed positions with relation to their respective tubes. It is also to be noted, that the hinged closures 3 are so mounted on the sides of the vessel as to swing downwardly when released.

85 In order that communication between the several tubes and the interior of the vessel may be established as desired, openings are formed in the sides of said vessel at 90 points in proximity to the mountings of the hinged closures 3 and are adapted to be closed by annular cover members 5 snugly receivable therein and hinged to the adjacent portions of the vessel in such a manner as to allow the same to be swung inwardly thereinto. Brackets 6 are pivoted to the several sides of the vessel at points adjacent the openings and are provided with screw threaded elements 7 serving as latch 100 means when they are turned into engagement with the adjacent free ends of the hingedly mounted closures 5. Thus, when the said closures 5 are engaged by the ele-

ments 7, the same will be prevented from swinging inwardly into the vessel thus, affording an effectual closure therefor and preventing the passage of water into said vessel. Of course, it is to be understood that various forms of packing may be arranged on the peripheral edges of the several closures 5 to insure water tight engagement between the same and the sides of the 10 openings receiving them. Dead-lights 8 may be and preferably are arranged in the closures 5 and allow the movements of an operator to be observed after the closures have been moved into engagement with the 15 openings for receiving the same.

As means for expelling any water which may accumulate in the tubes 2 after the closures 3 have been moved to their closed positions, pumping mechanism indicated in its 20 entirety by the numeral 9 is arranged therein and operated by a suitable source of power. It will be noted, that the exhaust conduit of the pumping mechanism is received in substantially frusto-conical openings 10 formed in the adjacent portions of the several closures 3. Hence, all water which has accumulated in the tubes subsequent to the closing of the closures 3 may be expelled previous to the opening of the 25 closures 5 and the entrance of the operators into said tubes.

Expansible coil springs or like devices designated by the numeral 11 are arranged adjacent the rear extremities of the several 35 tubes and arranged with follower plates 12, which plates serve as means for normally placing the mine or explosive devices arranged in said tubes under pressure and causing the same to be moved forwardly, 40 thereby facilitating the removal of the mines therefrom.

In order that the operators may be supplied with the necessary air and may at all 45 times be in communication with the occupants of the vessel, an air conduit 13 and telephone wires 14 are passed through the closures 5 into engagement with the head gears 15 of the diving suit of the operators. It of course will be understood that 50 the remaining ends of the conduit 13 and the wires 14 are engaged with a source of air supply and a usual electrical telephone. Further, a transmitter and receiver are arranged in the head gear of the diving suit, 55 and serve for an obvious purpose.

In operation, mines are of course arranged in the tubes 2 carried upon the opposite sides of the vessel. When desiring to lay mines while the vessel is submerged, the 60 pumping mechanism 9 is started to remove all water which may have accumulated in the tubes 2, whereupon one or both of the closures 5 are opened and an operator or operators pass through the openings in the

sides of the vessel. When in the tube, the 65 operator lies in a prone position as shown in the Fig. 2 and when desired, releases the windlass 4, thus allowing the closure 3 on which he is arranged to gradually move downwardly to a full open position due to 70 the weight thereon. When the closure is in its open position, the operator may move to standing position and engage and remove one or any number of the mines arranged in the adjacent tube 2. When the 75 mines have been removed, the operator may then leave the vessel and by proper manipulation, reach a point whereat it is desired to lay the mine or attach the same to the hull of a ship. After the mine has been 80 placed, the operator then, of course, returns to the vessel and while lying in prone position upon the closures 3 operates the windlass 4 to cause the moving of said closure into its closed position with relation to its 85 respective tube 2. The pumping mechanism 9 may be again started to remove all water from the tube, whereupon the closure 5 arranged in the communicating opening is removed; thus, allowing the operator to enter 90 the vessel.

From the foregoing, it will be readily understood by persons skilled in this art that I have provided an exceedingly efficient and simple submarine device, which may be advantageously used in warfare for the placing of mines, explosive devices or the like in the waterways of an enemy or to the bottom of the ships of an enemy without detection. The attachment may be used for various 100 other purposes not enumerated herein.

Manifestly, the construction shown is capable of considerable modification and such modification as is within the scope of my claims, I consider within the spirit of my 105 invention.

I claim:—

1. In combination with a submarine vessel, compartments arranged on the sides thereof and adapted to communicate with 110 the interior of the vessel at times, said compartments having exit means for permitting an operator to leave the same and for supporting the operator in working position.

2. In combination with a submarine vessel, tubular members secured to the opposite sides thereof and adapted to communicate with the interior of the vessel at times, said tubular members having exit means for permitting an operator to leave the same and 120 for supporting the operator in working position.

3. In combination with a submarine vessel, tubular members arranged on the sides thereof and adapted to communicate with 125 the interior of the vessel, at times, and hinged elements secured to the sides of the vessel conforming in shape to said tubular

members for closing the same and for supporting an operator in working position when opened.

4. In combination with a submarine vessel, compartments arranged on the sides thereof and adapted to communicate with the interior of the vessel at times, means for normally forcing articles forwardly in said compartments, and exit means in the compartments for permitting an operator to leave the same.

5. In combination with a submarine vessel, a tubular member adjacent one side thereof adapted to communicate with the interior of the vessel at times, the forward portion of said tubular member being removed, a closure conforming in shape to the tubular member for closing the removed portion therein, means for retaining said closure in its closed position and for permitting the same to be released as desired, the

side of the vessel adjacent the removed portion of the tubular member having an opening formed therein, and means for normally closing said opening.

6. In combination with a submarine vessel, a tubular member having its opposite ends closed arranged on one side thereof, a portion of the tubular member being removed, closure means corresponding in shape to said tubular member for closing the removed portion, means for retaining said closure in its closed position and permitting the same to be released as desired, the side of the vessel having an opening formed therein adjacent the removed portion of said tube, and means for normally closing said opening.

In testimony whereof, I affix my signature hereto.

CHRIST LARSEN.
